A. A. Fowler

Inventor.

Edward J. Worcester

UNITED STATES PATENT OFFICE.

EDWARD J. WORCESTER, OF WORCESTER, MASSACHUSETTS.

DRILLING-MACHINE.

SPECIFICATION forming part of Letters Patent No. 274,243, dated March 20, 1883.

Application filed April 6, 1882. (No model.)

To all whom it may concern:

Be it known that I, EDWARD J. WORCESTER, a citizen of the United States, residing at Worcester, in the county of Worcester and State of Massachusetts, have invented a new and useful Improvement in Drilling-Machines, of which the following is a specification.

My invention relates to self-feeding or blacksmiths' and carriage-makers' drilling-machines, and has for its objects to impart a feeding motion to the drill-spindle, to provide a wheel-rest for holding the carriage-wheel while drilling the tire, to vary the speed of the drill-spindle, and also to disconnect the balance-wheel from the drill-spindle at will.

15 The following is a full and exact description of my invention, reference being had to the accompanying drawings, in which—

Figure 1 shows a front view of the drilling-machine; Fig. 2, a side view; Fig. 3, a sectional view of the grinding device on the line $x-x$; Fig. 4, a detached view of the feeding device, and Figs. 5 and 6 detached portions of the feeding device.

25 Similar letters refer to similar parts in the several views.

The construction and arrangement of the main operating portions of my improved drilling-machine are similar to the self-feeding drilling-machines in ordinary use.

A represents the frame-work; B, the drill-spindle, having the beveled pinion C; D, the crank-hub, fixed to the driving-shaft by the set-screw f. C' is the driving beveled gear. 35 C'' is a spur-gear upon the driving-shaft, which imparts motion, through the intermediate, F, running loose upon the stud F', to the gear G and balance-wheel shaft G'. I is the balance-wheel.

40 On the main driving-shaft is the eccentric E, Figs. 1 and 4, which imparts a rocking motion to the bell-crank lever upon the stud H through the connecting-bar E'. The vertical and long arm H' carries the pawl a, whose forward motion gives a rotary motion to the crown ratchet-wheel b, whose hub, securely held in the frame-work, has an internal screw-thread, which, operating the screw swiveled to the upper end of the drill-spindle, gives a

vertically-sliding motion to the drill-spindle 50 in the manner common to self-feeding drilling-machines.

The end G of the balance-wheel shaft is fitted to receive the crank-hub D. The gears G and C'' are so proportioned that the speed 55 of the balance-wheel will be considerably greater than that of the driving-shaft, so that the motion of the drill-spindle will be slow when the crank-hub is fixed to and power imparted through the shaft G'. The intermediate gear, F, slides on the stud F', so it can be moved out of gear and the balance-wheel entirely disconnected from the driving-shaft, which is very desirable in many cases when small drills are used, or when the grinding device 60 is to be used independently of the drill-spindle. The use of the intermediate, F, also gives the same direction to the rotary motion of the shaft G' as the driving-shaft, and obviates the necessity of reversing the motion of 65 the crank when the drill is driven from the shaft G'. The short arm H'' of the bell-crank lever has a vertical slot, O, and an adjusting-screw, O', and the connecting-bar E' has its upper end forked to inclose the slotted end of 70 the arm H'', and has a pin, d, which passes through the slot O. When the adjusting-screw O' is withdrawn the reciprocating motion of the bar E', actuated by the eccentric E, is "lost" by the pin d, sliding in the slot O, and the 75 arm H'' will receive no motion; but if the screw O' is advanced upon the pin d, so that the "lost motion" is "taken up," the arm H'' will have a vibration equal to the throw of the eccentric E, the pawl a in its backward motion 80 passing over the teeth of the ratchet b. Thus it will be seen the amount of the feeding motion may be varied by the adjusting-screw O', no springs being required and both the backward and forward motion of the pawl being positive. 85

To the frame of the drill I attach the plate 1, having the swinging frame 2, hinged at its lower edge by the pins 8, and carrying in suitable journals at its upper edge the arbor 9, with the friction-wheel 5 arranged to revolve 90 in the same plane as the balance-wheel I. On the end of the arbor 9 is the grinding-wheel 3, and to the plate 1 is attached the "rest" 4,

which may be properly arranged to hold a twist or other drill in suitable position to have its bevel *o* accurately ground.

Upon the side of the sliding sleeve S are arranged the lugs K, supporting by the pins L the swinging-plate P, having at its lower end the pin N.

The screw M should pass through the plate P and just touch the sleeve S when the pin N is in a horizontal position, and may be adjusted to secure the proper position of the pin N. Upon the pin N the hub of a carriage or other wheel may be placed while the tire is being drilled, the wheel being turned on the pin N as the successive holes are drilled, thereby furnishing a support for the wheel without mar ring the wood-work of the wheel. The slide S both slides and turns upon the post T, allowing either the table J or the pin N to be brought beneath the drill, when it may be fastened in position by the set-screw s.

I am aware that drilling-machines have been constructed with a balance-wheel shaft geared directly to the driving-shaft, and having the speed of the drill-spindle varied by transferring the crank to the balance-wheel shaft and reversing the motion of the crank. I do not claim such a construction. Neither do I claim the construction and operation of the grinding device shown and referred to in the foregoing specification, nor the combination of a grinding device with a drilling-machine. These have been made the subject of a separate application; but

What I do claim is—

1. The combination of the ratchet-wheel *b*, vibrating bell-crank lever having arms H' and H'', connecting-bar E', and eccentric E, as described, and for the purposes set forth.

2. The combination of the ratchet-wheel *b*, bell-crank lever with arms H' and H'', slot O and adjusting-screw O', and the connecting-bar E', actuated by the eccentric E, and having the pin *d*, as described, and for the purposes set forth.

3. The combination, with the drill-shaft B, having the beveled pinion C, and the driving-shaft having the beveled gear C', the gear C'', and crank-hub D, of the sliding intermediate pinion, F, and balance-wheel shaft having the wheel I and gear G, as described, and for the purposes set forth.

4. The combination, with the drill-spindle B and post T, of the sliding sleeve S, and a wheel-rest consisting of a pin, N, as described, and for the purposes set forth.

5. The combination, with the drill-spindle B, post T, and sliding sleeve S, of a wheel-rest consisting of a pin, N, and swinging plate P, with adjusting-screw M, as described, and for the purposes set forth.

EDWARD J. WORCESTER.
